UNITED STATES PATENT OFFICE.

JOSEPH F. KENNEDY, OF CHICAGO, ILLINOIS.

ERASER HOLDER.

Application filed May 13, 1925. Serial No. 30,110.

My invention relates to a holder for a blackboard eraser, and its object is to provide a holder which may be attached to a chalk rail, for example, of any design and contour; which may be readily removed from its place of attachment, for instance from the chalk rail for the purpose of cleaning the rail; which will be slightly in appearance and strong and rigid in construction; and which may be manufactured at relatively low cost.

The invention is illustrated in the preferred embodiment in the accompanying drawing, wherein—

Fig. 1 is a view, in perspective, of the improved eraser holder shown as attached to the chalk rail of a blackboard.

Fig. 2 is a sectional plan view on line 2—2 of Fig. 1, the scale being enlarged.

Fig. 3 is a plan view of the eraser retaining member of the device.

Fig. 4 is a view, in perspective, of one of the retaining member locking lugs.

Fig. 5 is a view, in perspective, of the fixed member or attaching plate to which the retaining member is attached, and

Fig. 6 is a cross sectional view of the attaching plate indicated by line 6—6 of Fig. 5 but with the plate secured to the chalk rail.

Referring to the drawing, 10 designates the blackboard and 11 a chalk rail of ordinary construction.

The eraser holder consists of an attaching plate 12 which is preferably set into a recess 13 in the forward edge 14 of the chalk rail so that the plate is flush with said edge, and an eraser retaining member 15 consisting preferably of a sheet of metal and formed with rearwardly projecting wings 16, 16, the metal being preferably cut away, as indicated at 17, 17.

The attaching plate 12 is shown as secured to the rail by screws 18 and is formed with longitudinally tapered slots 19, 19, the inner edges of which are beveled, as indicated at 20 (Fig. 6). The slots 19 are formed with enlargements 21, 21.

The retaining member is provided with locking lugs 22, corresponding in number to slots 19, which are wedge-shaped, transversely, and are also preferably tapered longitudinally, all as indicated in Fig. 4. The lugs may be provided with studs 23 to extend through perforations in the retaining member after which the studs may be up-

set so as to hold the lugs rigidly to the retaining member.

Preferably the retaining member is bowed slightly, as indicated in Fig. 3. It is engaged with the attaching plate 12 by placing the locking lugs in the enlargements 21 of slots 19 and then moving the member toward the small ends of the slots. This brings about a wedging engagement between the lugs and the beveled edges of the slots and this engagement is preserved by the bending or straightening out of the forward or body portion of the retaining member.

By this arrangement the retaining member may be very easily removed from the chalk rail for the purpose of cleaning the chalk dust from the rail. The engagement between the retaining member and the plate 75 when the parts are brought together, is a rigid and strong engagement.

While I have illustrated and described the invention in a preferred embodiment I desire to be understood as claiming all 80 modifications within the scope of the appended claims.

I claim:

1. In a device of the character described, the combination of a slotted plate and an 85 eraser retaining member which is flexible, bowed in the direction of its length and formed with undercut lugs to engage the slots in said plate.

2. In a device of the character described, 90 the combination of a plate formed with tapered slots having their inner edges beveled, and an eraser retaining member formed with undercut, wedge-shaped lugs to engage the slots in the plate, said eraser retaining 95 member being flexible and bowed in the direction of its length.

3. An eraser holder comprising, in combination, a plate formed with tapered slots having beveled inner edges and enlargements at one end thereof, and a sheet metal retaining member formed with inwardly projecting wings and provided with beveled lugs adapted to engage with and to be disengaged from said tapered slots by movements of the retaining member in the direction of its length.

4. An eraser holder comprising, in combination, a flat plate formed with tapered slots having beveled inner edges and enlargements at one end thereof, and a sheet metal retaining member formed with in-

wardly projecting wings and provided with beveled lugs adapted to engage with and be disengaged from said tapered slots by movements of the retaining member in the direction of its length, said retaining member being flexible and slightly bowed so that it is bent to straight by engagement with said plate.

5. An eraser holder comprising a flexible resilient sheet metal eraser retaining mem-

ber, attaching means adapted to be fixed to a blackboard chalk rail, and means on the inside of said retaining member adapted to be engaged with said fixed attaching means so that the retaining member covers said fixed attaching means and is sprung out of normal shape and thus put under strain which resists its removal from the chalk rail. 15

JOSEPH P. KENNEDY.
